UNITED STATES PATENT OFFICE

DAVID A. MCINTYRE, OF NEWARK, NEW JERSEY, ASSIGNOR OF ONE-HALF TO EMIL L. MUELLER, OF NEWARK, NEW JERSEY

METHOD OF PAGE NUMBERING SHEETS FOR BOOKS

Application filed July 7, 1927. Serial No. 204,108.

This invention relates to a method for page-numbering sheets for books, and an object of the invention is to provide an improved method by means of which the numbering of pages may be simplified and expedited.

In the making up of books it is customary to form the same of a plurality of separate sections each section consisting of two or more separate sheets of paper folded midway so that each sheet provides two leaves and four pages and so that in each section these sheets will be connected together to form a section, or signature, of suitable thickness for handling and binding. In order to properly number the pages so that they will read consecutively through the several sections of the book it is apparent that numbers placed on the succeeding sheets as they issue from the main printing press, or otherwise, will not be in numerical sequence, and it is therefore an object of the present invention to provide a method which will be readily adapted to the printing of correct numbers in appropriate sequence so that when the sections, or signatures, are made up and bound into a book the numbers will appear in proper numerical sequence in the completed book.

In certain forms of books, such as in record books of different types, it is desirable that each two adjacent pages throughout the book be numbered with identical numbers so that the two pages appearing for inspection whenever the book is laid open will have the same number, and it is therefore a further object of the present invention to provide a method of so numbering the sheets that when they are bound into sections, or signatures, and the sections are placed side by side in the book the pages appearing for inspection as indicated will bear like numbers.

A further detailed object is to provide a method according to which sheets fed one after another through a printing mechanism and consecutively printed with different page numerals at different points thereon will, upon issuing from the printing mechanism in signature form, present their page numerals in numerical sequence throughout

the signatures individually and collectively.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of device by which to perform the present method:

Fig. 1 is a diagrammatic side elevational view of a portion of a numbering machine.

Fig. 2 is a top plan view, partly in section, of the structure appearing in Fig. 1.

Fig. 3 is a view illustrating two simple book sections such as may be numbered by this machine.

Fig. 4 is a diagrammatic view, similar to that seen in Fig. 1, but on a smaller scale, and illustrating an arrangement whereby the four page numbers usually required upon each sheet of paper in a book may be applied by the use of only two platen wheels whereas in the arrangement suggested by Fig. 1 four separate platen wheels are required, and

Fig. 5 is a view similar to Fig. 3 but showing a different arrangement of page numbers.

In order to fully understand the present method and its mode of application a detailed description of the mechanism illustrated will be of assistance as follows, said mechanism corresponding to that shown and described in the pending application of Emil L. Mueller, Serial No. 24,728:

The reference character L indicates a type-wheel about the periphery of which is a series of spaced projections as 1, 2 and 3 the outer peripheral faces of which are each cut or otherwise formed as printing type each projection being shaped to provide a different figure and there being as many projections as there are separate sheets of paper to be numbered for comprising the book in course of being printed.

Adjacent to the type-wheel is a platen wheel G carrying a single platen member H on the periphery thereof which is adapted to press an interposed sheet as 4 against one of the type-projections on the type-wheel.

Any suitable means may be employed for holding the sheet 4 and causing it to be carried around with the wheel G, there being indicated for this purpose a suitable gripper 5 arranged to engage the forward edge of the sheet as the sheet comes off of a delivery table 6 and to clamp said edge of the paper against a part 7 of the platen wheel in a well understood manner.

15 The table 6 may be understood to be a part of the main printing press by means of which the sheet has been previously printed, or otherwise treated, so that it contains all of the reading matter or otherwise preparatory to binding.

The platen member H is preferably adjustable circumferentially of the wheel G and for this purpose the drawings indicate said member as being formed upon a carrying plate 8 which laps over the side of the wheel G and which carries retaining devices 9 extending into an undercut groove 10 formed circumferentially of the wheel G. By loosening the devices 9 the platen member may be slid around the wheel G, the devices 9 meanwhile sliding in the groove 10, to any position desired and may be held in such position by tightening the devices 9. By this means the platen member may be caused to stand nearer to or further from the clamp member 5 and therefore nearer to or further from the forward edge of the sheet 4 so that the figure from the type-wheel may be impressed at a selected position upon the sheet.

40 It will be understood that in order to properly complete this adjustment the wheels L and G are at that time freely rotatable relative to each other so that any selected type-projection on the type-wheel may be made to register with the platen member.

It is intended that after the sheet, as 4, has passed between the wheels L and G and has received therefrom the impression of one figure from the type-wheel it will then pass between two further wheels for receiving the impression of a second figure, then between two further wheels for receiving the impression of another figure, and finally between a fourth pair of wheels to receive 55 the final figure, thus impressing onto the sheet, and in proper locations thereon, the page numbers of the four pages which the sheet is to comprise when fixed in place in the book.

60 In the drawings Fig. 1 there is shown in association with the wheels L and G a portion as 11 of the next pair of wheels for operating upon the sheet after the sheet has passed between the wheels L and G. Adjacent to the under-side of the wheel G is a

table 12 upon which the sheet 4 will be deposited after leaving the wheel G. Any suitable means, as for instance the push device 13, may be employed in association with the table 12 to slide the sheet 4 off of said table and onto the wheel 11 where it will be gripped and carried on its way.

70 The sheet will pass similarly through the four sets of wheels but since each set is of identical construction and operation only one set is herein shown and described in detail.

75 The wheels L and G are fixed to suitable carrying shafts 14 and 15 respectively. These shafts are mounted in appropriate bearings 16 and 17 formed in a frame piece 18. Upon the shaft 14 is mounted a gear 19 which is freely rotatable upon said shaft and which stands in constant mesh with a gear 20 fixed upon the shaft 15.

80 Upon the shaft 14 is a second gear 21 which is fixed to said shaft and which stands in constant mesh with the teeth of a drive pinion 22. The pinion 22 is mounted upon a bearing shaft 23 and is connected to be driven by any appropriate means as for instance a drive gear 24.

85 Mounted upon the shaft 14 is a third gear 25 also standing in constant mesh with the same teeth of the pinion 22 as the gear 21. The gear 25 however, although of the same pitch diameter as the gear 21 has one tooth less than said gear 21 and on this account will rotate at a slightly faster speed than the gear 21, a complete rotation of the gear 21 being in fact accompanied by a complete rotation of the gear 25 plus the distance of one tooth of the gear 25.

90 The gear 25 is connected with the gear 19 by a suitable clutch device, as for instance the pin 26 carried by the gear 25 and engaging within a socket 27 provided in the gear 19, so that said gear 19, and consequently the gear 20, both of which are of the same pitch diameter, will rotate with the gear 25, as will also the wheel H.

95 The gear 21, being fixed to the shaft 14, will cause the wheel L to move with it and consequently at a correspondingly slower speed than the wheel G.

100 There are as many type-projections on the wheel L as there are teeth in the gear 25. The type-projections are thus spaced apart a distance corresponding to the distance between the teeth of the gear 25 and it will be apparent therefore that each time the platen member H comes around into contact with the type-wheel it will engage a succeeding type-projection of said type-wheel.

105 Referring to Fig. 1 the platen member is shown as in engagement with the type-projection carrying the figure 1. At the first rotation of the two wheels the platen member will come into engagement with the type-projection carrying the figure 2. At the next

85

120

125

130

rotation it will come into engagement with the type-projection carrying the figure 5. At the next rotation it will come into engagement with the type-projection carrying the figure 6, and so on.

When the full cycle of the type-projections on the wheel L has been completed a new cycle will begin without interruption, and here it will be noted that the total number of type-projections on the wheel L is determined by the total number of pages which are to appear in the book being printed. The wheel L would carry projections for one-fourth of the total number of pages and the corresponding wheel of the other three sets of wheels would each carry another fourth.

The figures appearing upon the type-projections of the several wheels will of course be given a sequence according to requirements. Assuming, for example, that the machine is being utilized for printing the four sheets of paper comprising the two book sections illustrated in Fig. 3, and noting that in these book sections the adjacent pages bear like numbers, the first pair of wheels, as L and G, will print onto the first sheet the page number, or figure, 1, onto the second sheet the page number 2, onto the third sheet the page number 5, and onto the fourth sheet the page number 6. The second pair of wheels would print on the first sheet the page number 4, onto the second sheet the page number 3, onto the third sheet the page number 8, and onto the fourth sheet the page number 7. The third pair of wheels would print onto the first sheet the page number 3, onto the second sheet the page number 2, onto the third sheet the page number 7, and onto the fourth sheet the page number 6. The final pair of wheels would print nothing on the first sheet, onto the second sheet it would print the page number 1, onto the third sheet the page number 4, and onto the fourth sheet the page number 5.

As these sheets issue one after the other from the machine and are folded into sections as indicated in Fig. 3 the page numbers would read in proper sequence as illustrated.

The gear wheels 21, 22 and 25 and the type-wheel L constitute a unit, that is to say they are co-operative with each other to properly number the pages of a book having a given number of pages. In order to number the pages of a book having a different number of pages the parts comprising this unit would be removed and substituted by another unit the parts of which would be co-operative in the same manner but there being a different number of type-projections on the type-wheel and a correspondingly different number of teeth in the gears. In the instance illustrated the gears 21 and 25 may be readily detached by removal of the retaining pin 28. The pinion 22 may be removed by removal of its retaining pin 29, and the type-wheel may

be removed by removal of its retaining pin 30.

Any suitable means, as for instance the ink roll 31 may be provided for inking the printing surface of the type-projections on the type-wheel.

While this invention is applicable to the printing of page numbers in various types of books it is nevertheless peculiarly adapted to the numbering of pages in books where the printed matter on all of the pages is alike, as for instance in certain classes of receipt and record books such as are used by connecting agents for insurance companies and other large organizations, since in these instances the page numbers may be readily applied by this invention upon the succeeding sheets as they issue from the main printing press in the manner above described and thus the book sections, and finally the books, may be printed one after the other ready for immediate binding. Any desired number of books may be thus printed and bound wholly without reference to how many books are required or how many have been printed, or otherwise, as has been an aggravating requirement in the numbering of pages of this class of books heretofore.

As has been hereinabove suggested the modification Fig. 4 offers an arrangement whereby the use of two of the platen wheels required for printing the page numbers at the four different localities as described with respect to Fig. 1 may be omitted. Instead of employing four separate units each containing a platen wheel and a printing wheel the illustration Fig. 4 proposes only two separate units each comprising a platen wheel as G and two printing wheels 32 and 33. As the sheet of paper as 4 passes about the first platen wheel it receives the impression of two page numbers at proper locations thereon from the two printing wheels associated with that platen wheel, these impressions being of course both on the same surface of the sheet. Upon leaving the first platen wheel the sheet is caught by the gripper 5 and carried around the second platen wheel. In passing around the second platen wheel it receives the impression of two page numbers at proper locations on its opposite surface by means of the pair of printing wheels 32 and 33 associated with the second platen wheel, after which it is deposited onto the delivery table 34.

Suitable means will of course be provided to prevent the different platen members H on each platen wheel from producing impressions from more than one printing wheel, as for instance the platen members may be placed slightly out of alignment with respect to each other, as will likewise the printing wheels, so that no printing pressure will be produced excepting against the type of the proper printing wheel.

It will be understood of course that the drive mechanism for the wheels suggested by this modification will be substantially the same as already set forth with regard to the disclosure Figs. 1 and 2.

Although the above description is applied to sheets folded only a single time for forming only four pages, obviously the principle of operation will apply equally to sheets folded two or more times for forming additional pages. There will be a separate printing wheel for each page and the character of the various printing wheels will be arranged in proper order for impression upon the respective page-spaces of the sheet as will be readily understood.

From the foregoing the improved method of page-numbering sheets for books will be apparent, namely, that the sheet are fed one after the other through the mechanism, passing separate printing wheels, as 32 and 33 associated with platen wheel G, said printing wheels consecutively printing different page numerals on spaced portions of one surface of each sheet, the sheets then passing other printing wheels, as 32 and 33 associated with platen wheel H, the latter printing wheels consecutively printing different page numerals on spaced portions of the other surface of each sheet, the printing of all of the page numerals being in such relation, as to placement and numerical arrangement, that when the sheets leave the mechanism and are assembled in sections or signatures the numbering of the pages of each section or signature, and in fact of the several sections or signatures collectively, will be in numerical sequence.

It is understood that the term "numerical sequence" is intended to comprehend either an arrangement of the numbers such that each adjacent page is differently numbered and in sequence, or an arrangement of the numbers such that two opposing pages throughout the section or sections will have similar numerals, the pairs of numerals in this latter instance being in sequence.

Having thus described my invention, what I claim as new and desire to secure by Letters Patent is —

1. The herein described method of page-numbering sheets for books, which method consists in feeding a sheet and printing page numerals on spaced portions of one face of the sheet, continuing to feed the sheet and to print page numerals on spaced portions of the opposite face of the sheet, feeding sufficient other sheets to make up a signature and printing page numerals upon the opposite faces of said other sheets successively in the manner mentioned for the first sheet, placing said sheets in pile formation in the order as they are successively printed, and then folding the pile into signature form, the arrangement of the numerals printed

upon the two faces of all of the sheets being such that when the sheets are thus folded in signature form the page numerals appearing upon the signature will be in a predetermined sequence.

2. The method of page numbering sheets for books consisting in feeding a sheet and consecutively printing different non-consecutive page numerals on spaced portions on one face of the sheet, continuing feeding of the sheet and printing different non-consecutive page numerals on spaced portions of the opposite side of the sheet in such relative relation that when the sheets are assembled in a signature the page-numerals appearing upon the signature will be in a predetermined sequence.

3. The method of page numbering sheets for books consisting in feeding a sheet and consecutively printing different non-consecutive page numerals on spaced portions of one face of the sheet, continuing feeding of the sheet and printing different non-consecutive page numerals on spaced portions of the opposite side of the sheet in such relative relation that when the sheets are assembled in a signature two opposing pages will have similar page numerals.

In testimony whereof I affix my signature.

DAVID A. MCINTYRE.
